L. A. KEMPTON

FLUSH WALL SWITCH

Filed Sept. 27, 1924

Fig.1.

Fig.2.

UNITED STATES PATENT OFFICE.

LESLIE A. KEMPTON, OF BRIDGEPORT, CONNECTICUT, ASSIGNOR TO GENERAL ELECTRIC COMPANY, A CORPORATION OF NEW YORK.

FLUSH WALL SWITCH.

Application filed September 27, 1924. Serial No. 740,411.

The present invention relates to electric switches and more especially to switches for use in connection with house wiring systems of the flush wall type and adapted to be installed in mortises cut into the plastered wall with only the flush wall plates and the operating means outside the face thereof.

In order to conserve to the utmost the floor space in dwelling houses and office buildings, the partition wall have been reduced in thickness, so much so that the flush switches heretofore on the market, if installed in one plastered surface thereof, would extend through and outside the opposite plastered surface.

The object of my invention is the production of an improved flush wall switch which shall be adapted for installation in thin house partitions, which shall be adapted to break full capacity circuits, which shall be adapted to withstand continued rough usage, and which may be manufactured at low cost.

One embodiment of the invention is shown in the accompanying drawing, in which Fig. 1 is a perspective view of the base and wire connectors; Fig. 2 is a similar view of the switch mechanism detached from the base; Fig. 3 is a similar view of a cardboard protector for the switch mechanism; Fig. 4 is a side elevation of the switch frame; Fig. 5 is a longitudinal section of the complete flush switch; Fig. 6 is a rear elevation of the switch mechanism, and Figs. 7, 8 and 9 are perspective views of detail parts.

The base 1 is in the form of a shallow box of insulating material, such as porcelain, with means for attachment of electric wires thereto consisting of metal plates 2 secured to the base by screws 3 and each provided with a binding screw 4 and a stationary switch contact 5. The depth of the base 1 for the construction of switches for use on ordinary house circuits is only one inch, whereas switches heretofore on the market have ranged from one and five-eighths inches to over two inches in depth.

The main frame of the switch mechanism comprises a sheet metal bridge member 6 extending longitudinally of the box and attached to the end walls thereof by screws 7. The ends of the bridge pieces are provided with the usual screw holes 8 and positioning extensions 9. Adjacent its middle the bridge is provided with two apertures 10 for the

passage of the push buttons 11 and at opposite edges of the middle are webs 12 bent back at a right angle thereto. In order to render the frame rigid despite the large amount of metal removed incident to the formation of the apertures 10, I extend the webs integrally about the holes in crown-shaped flanges 13. Both webs 12 are shaped as indicated in Fig. 4 with wide rear ends provided with spaced stop shoulders 14, while the intermediate waist portion is provided with an open slot 15 and an aperture 16 for the rocker shaft 17. The slot is so formed at its forward part as to provide spaced stop shoulders 18 symmetrically disposed with relation to the shaft aperture 16, while its rearward part is provided with an arc-shaped bearing 19 in the horizontal plane of the shaft aperture.

Owing to the necessity of conserving depth space, the rocker shaft 17 is located adjacent the main portion of the bridge 6 and the switch-actuating rocker 20 is in consequence designed to operate very close to the bridge 6. The actuating rocker 20 is shaped as indicated in Figs. 5 and 7 from sheet metal with triangularly-shaped side portions 21 integrally connected at the wider or front ends by transverse straps or shoulders 22 of a length to permit the rocker to be assembled in the space between the side webs 12 of the bridge and each side portion 21 is provided at its middle front edge with an apertured lug 23 adapted to engage the shaft 17 and at its rear edge with an open key hole slot 24 for the pivotal reception therein of the spring thrust plate 25. The side portions 21 of the actuating rocker are also provided at their centers with struck up stop lugs 26 adapted to project a short distance outside the side webs 12 of the bridge member and to engage at the ends of the opposite movement of the rocker with stop shoulders 18.

The spring 27 for producing the snap movement is of the ordinary helical compression type and is assembled about a guide rod 28 and thrusting at its rear end against a stop plate 29 fixed transversely upon the guide rod 28 a short distance from the end thereof as indicated in Fig. 5, while its forward end thrusts against the spring plate 25 provided with a central aperture through which the guide rod 28 plays and having at its opposite edges pintles 30 adapted to enter

the key hole slots 24 at the rear end of the actuating rocker 20.

The driven rocker 31 is also of sheet metal bent U-shape and of a width to be assembled 5 outside the webs 12 of the bridge member 6. Each leg of the rocker 31 has at its free end a semi-cylindrical pivot 32 forced inwardly and adapted to engage the arc-shaped bearings 19 in the bridge webs 12. The ends of 10 the legs are bifurcated to provide horns 33 at opposite sides and forward of the pivots 32 adapted to be engaged by the lugs 26 of the actuating rocker 20 to positively start the actuated rocker 31 in case of sticking thereof. One or both of the legs of the 15 driven rocker 31 has posts 34 bent outwardly from its edges opposite the pivot 32 and on these posts the switch blade 35 is secured with intervening insulation 36. The connecting member of the U-shaped rocker 31 20 is adapted to engage the respective stop shoulders 14 at the ends of its swing and limit the extent of movement of the switch blade 35 and is centrally apertured for the reception of the rear or pivotal end of the 25 guide rod 28 of the snap spring.

In order that the push buttons 11 may move tangentially to the arcs of movement of the ends of the actuating rocker 20 and, 30 owing to the necessary proximity of the pivotal axis 17 of the rocker to the bridge member 6, special means of engaging the buttons 11 with the rocker 20 are provided. Each button 11 comprises an insulating outer portion with a metal shank 37 secured to the rear end thereof and provided with a side lug 38 disposed partly within the insulating outer portion and partly in rear thereof and in this side lug is a V-shaped slot with the 35 mouth adjacent and adapted to receive therein a transverse shoulder or strap 22 of the actuating rocker 20 so that throughout the travel thereof there is no cramping of the parts upon each other nor is there lost motion between them.

To provide against undue tilting of the push buttons, particularly in their outer positions, a freely rocking guide plate 39 is provided for the inner end of each shank 37. 40 The guide plates 39 have central guide apertures corresponding to the cross sectional shape of the shank and each is provided at its ends with pivots 40 adapted to be received in apertures 41 in the opposite webs 45 12 of the bridge member 6.

As a means for protecting the switch mechanism from the entrance of foreign matter and persons from injury from electric arcing when the face plate 42 is unattached and to prevent an arcing current being short circuited by the face plate when the latter is attached to the switch, I provide a cardboard protector 43 adapted to cover the base 1 and the parts contained 50 herein, except the wire terminals 2 which

are necessarily left uncovered to permit of attachment of the wires without interference with the protector. The ends of the protector are provided with projecting lugs 44 and these are adapted to be embraced and 55 securely held to the bridge 6 by soft metal clips 45, as shown in Fig. 2, each having a central eye 46 therein and disposed with the central portion between the base and bridge member where it is bound by the attachment 60 screw 7, while the outer ends 47 are designed to fold over the lugs 44. In case it becomes necessary to remove the protector 43 for any reason, the clip ends 47 are easily 65 bent out and the protector removed without 70 injury.

The flush wall plate 42 is of usual construction and is secured to the bridge member 6 by screws 48.

While I have shown and described the 75 best embodiment of the invention known to me, I do not desire to be restricted thereto.

What I claim as new and desire to secure by Letters Patent of the United States is:

1. A two button electric switch having a 80 bridge member provided with passageways for the buttons and integral side webs bent into parallelism from opposite sides of the center thereof and said side webs having arcuate extensions about said passageways. 85

2. A two button electric switch having a bridge member provided with passageways for the buttons and integral webs extending in parallelism from opposite edges thereof, push buttons having shanks movable between 90 said side webs and guide plates for said shanks freely pivoted to said side webs. 100

3. An electric switch having a bridge member provided with button passageways, push buttons provided with shanks having 105 V notches formed therein, an actuating rocker pivoted immediately adjacent to said bridge member between said passageways and comprising two side members connected by two flat straps in the plane of its pivot adapted to enter the notches of said shanks, and means for guiding the inner ends 110 of said shanks. 115

4. An electric switch having a bridge member, parallel side webs connected to said bridge member and provided with open slots forming at their front ends spaced shoulders and at their rear ends arcuate bearings, an actuating rocker pivoted between said side webs adjacent the bridge member and having 120 stop lugs adapted to engage said shoulders, an actuated rocker of U shape disposed outside of said webs and provided with crown flanges adapted to enter said arcuate bearings, and spring means between said rockers. 125

5. An electric switch having a bridge member, parallel side webs connected to said member and provided with slots having spaced stops, an actuating rocker pivoted between said webs adjacent said bridge mem- 130

ber and having stop lugs extending through said web slots, an actuated rocker of U shape pivoted outside said webs and having the ends of its legs bifurcated to straddle said stop lugs, and spring means connecting the free ends of said rockers.

5. An electric switch having an open side base, a bridge member attached to said base over the opening therein, flexible clips

secured between said bridge member and said base, and a protector of sheet material overlying the open side of said base and detachably secured to said bridge by said flexible clips.

In witness whereof, I have hereunto set 15
my hand this nineteenth day of September,
1924.

LESLIE A. KEMPTON.
